CLAIM

The ornamental design for a dental aligner case, as shown and described.

DESCRIPTION

FIG. 1 is a top perspective view of a dental aligner case in a closed configuration.

FIG. 2 is a front view of the dental aligner case shown in FIG. 1.

FIG. 3 is a back view of the dental aligner case shown in FIG. 1.

FIG. 4 is a top view of the dental aligner case shown in FIG. 1.

FIG. 5 is a bottom view of the dental aligner case shown in FIG. 1.

FIG. 6 is a left side view of the dental aligner case shown in FIG. 1.

FIG. 7 is a right side view of the dental aligner case shown in FIG. 1.

FIG. 8 is a top perspective view of a dental aligner case such as the one shown in FIG. 1 in an open configuration.

FIG. 9 is a front view of the dental aligner case shown in FIG. 8.

FIG. 10 is a back view of the dental aligner case shown in FIG. 8.

FIG. 11 is a top view of the dental aligner case shown in FIG. 8.

FIG. 12 is a bottom view of the dental aligner case shown in FIG. 8.

FIG. 13 is a left side view of the dental aligner case shown in FIG. 8; and,

FIG. 14 is a right side view of the dental aligner case shown in FIG. 8.

In the drawings, the broken lines depict environmental subject matter only and form no part of the claimed design.
